UNITED STATES PATENT OFFICE

2,625,901

BURGLAR ALARM

Walter W. Flugrath, New Braunfels, Tex.

Application September 12, 1949, Serial No. 115,200

1 Claim. (Cl. 116—91)

1

The present invention relates to new and useful improvements in burglar alarms and more particularly to a spring-actuated bell clapper held inactive by a locking mechanism and which is released by the opening movement of a door or the like.

An important object of the invention is to provide both a manually controlled and an automatically controlled locking mechanism for the bell clapper for rendering the alarm mechanism inoperative when desired, to permit the door or other alarm releasing medium to be freely opened and closed at will without sounding the alarm.

Another object is to provide an alarm which may be easily and quickly installed in position on a door frame without necessitating any changes or alterations therein, and which, at the same time, is simple and practical in construction, efficient and reliable in operation, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the alarm mounted in position on a door frame;

Figure 2 is an enlarged top plan view of the alarm;

Figure 3 is a sectional view taken on a line 3—3 of Figure 2;

Figure 4 is an enlarged transverse sectional view taken on a line 4—4 of Figure 2;

Figure 5 is an enlarged sectional view taken on a line 5—5 of Figure 2; and

Figure 6 is an enlarged perspective view of the manual locking means for the clapper.

Referring now to the drawing in detail, wherein, for the purpose of illustration, I have disclosed a preferred embodiment of my invention, the numeral 5 designates the alarm casing which is open at its top and formed at its upper edge with attaching flanges 6 for attaching to the under side of the header 7 of a door frame. The casing is also provided with removable sides 8 held in position by bolts 9.

A frame 10 is secured to sides 8 of the casing by bolts 11, the frame including a pair of side frame members 12 secured together by bolts or the like 13 having spacing sleeves 14 to hold the sides of the frame spaced from each other.

A key-wound spring motor 15 of a convention-

2

al type is supported in frame 10 and includes a spring-driven gear 16 engaging a pinion 17 secured to a shaft 18 journaled in frame 10.

A toothed escapement wheel 19 is also secured to shaft 18 and is alternately engaged by a pair of lugs 20 on a clapper or bell hammer arm 21 which is fixed to a pin 22 slidably and rotatably supported in frame 10 and which projects outwardly of the casing and is provided with a knob 23.

Pin 22 is formed with a pair of annular grooves 24 in which the free end of a resilient finger 25 is selectively seated, the finger being fixed at its other end to one of the spacing sleeves 14.

An extension 26 projects rearwardly from clapper arm 21 and is provided with a lateral stop 27 movable into and out of engagement with a stationary stop 28 attached to frame 10 when pin 22 is moved inwardly or outwardly, to thus lock clapper arm 21 and escapement wheel 19, when desired.

The escapement wheel 19 is also locked to hold shaft 18 and clapper 21 inactive by means of a lug 30 on a bar 31 sliding in frame 10 and having one end slidably in casing 5 to project outwardly at both sides thereof and provided at its outer ends with push and pull buttons 32 to manually lock the alarm.

A rod 33 extends downwardly from bar 31 in the path of a rod 34 extending horizontally from one side of a bar 35 which is also slidably in frame 10 and projects outwardly at one side of casing 5. A coil spring 36 is held under tension on bar 35 between frame 10 and rod 34 to project bar 35 and to normally hold lug 30 disengaged from escapement wheel 19.

A bell 37 is supported on frame 10 in position to be struck by clapper 21.

In the operation of the device, casing 5 is attached to the under side of header 7 of a door frame and with bar 35 positioned toward the outside of the door frame for engagement by a screen or other door 38 to push bar 35 inwardly when the door is closed. Knobs 23 and 32 are positioned at the inner side of the door frame for manual actuation without interference by the door.

Knob 23 is pushed inwardly while spring motor 15 is being wound to move stop 27 in engagement with stop 28 to prevent movement of clapper arm 21 and escapement wheel 19.

When the alarm is set for sounding by an opening of the door, knob 23 is pulled outwardly, releasing stop 27, and knob 32 is also pulled outwardly, which then locks escapement wheel 19 by

55

engaging lug 30 on bar 31 with the wheel. As soon as the door is opened, spring 36 will move bar 35 outwardly, carrying pin 34 with it, which also moves pin 33 in a direction to slide bar 31 inwardly and releases lug 30 from escapement wheel 19 to set the clapper arm 21 in motion and sound the alarm.

Having described the invention, what is claimed as new is:

A closure alarm comprising a spring motor, a bell, a bell clapper pivotally mounted for oscillation to ring the bell, an escapement mechanism operative in conjunction with said motor to oscillate the clapper and including a toothed escapement wheel, an escapement wheel lock comprising a slidably mounted bar movable into unlocking position, a spring projected slidably mounted member held in retracted position by said closure and released for projection by opening of the closure, and means operatively connecting said member to said bar for moving said bar into unlocking position during projection of said member, said member being movable into retracted position by closing of said closure so that the closure may be closed while said bar is in unlocking position, said means comprising a

rod on said bar, and a rod on said member for engagement with one side of the first named rod.

WALTER W. FLUGRATH.
